J. ALTMAN.

Gun-Lock.

No. 16,634.

Patented Feb. 17, 1857.

UNITED STATES PATENT OFFICE.

JONATHAN ALTMAN, OF ARMSTRONG COUNTY, PENNSYLVANIA.

SELF-SETTING HAIR-TRIGGERED GUN-LOCK.

Specification of Letters Patent No. 16,634, dated February 17, 1857.

To all whom it may concern:

Be it known that I, JONATHAN ALTMAN, of the county of Armstrong and State of Pennsylvania, have invented a new Gun-
5 Lock, and that the following is a full, clear, and exact description of the principle or character which distinguishes it from all other things before known and of the usual manner of making, modifying, and using
10 the same, reference being had to the annexed drawings.

Figure 1 shows the lock and all its parts in the position when the gun is "cocked" ready for firing. Fig. 2, shows the trigger 15 plate and the parts connected with it, detached and exhibits these parts in their respective positions, when the hammer is down; Fig. 3, a top view of the lock.

The object of the above stated improvements is to produce a gun lock which will set the triggers of a double or hair triggered gun by the mere act of drawing back the hammer or as it is commonly called "cocking" the gun. It may therefore be
20 described as a self setting hair-triggered gun lock.

The improvement is intended to apply to those locks in common use for double triggered rifles. In those locks now in use
25 there is a lever constituting the upper part of the tumbler which is moved by the motion of the hammer as on a pivot. This lever or shaft in my improved lock is lengthened and extended (as shown at A,) 30 in toward the breech of the gun so that the end may work clear of the tumbler. To

that end of the said lever next the breech is pivoted another lever B of a shape slightly curving downward toward the trigger, the free end of which acts upon one 40 arm of a double lever C now to be described. This double V shaped lever is pivoted to a standard D on the trigger plate just in front of the hair trigger. One prong of this V lever curves downward to 45 the hind trigger E so as to act on said trigger when the hammer of the lock is drawn backward. The other prong of said double lever curves upward and is acted upon by the before mentioned lever B that is fastened to the end of the shaft or lever at the upper part of the tumbler.
50

When the hammer is drawn backward and the gun is cocked at a single draw, the lever B is projected forward against the end 55 of the one prong of the double lever, and moving it downward moves at the same time the other prong against the main trigger E of the gun the end of which is forced under the catch in the head of the hair trigger F and thus the triggers are set. The triggers may be set also by drawing back the hind trigger in the ordinary way.
60

What I claim as my invention is—

The mode herein described of setting the 65 double trigger lock by the act of cocking the gun as set forth.

JONATHAN ALTMAN.
